UNITED STATES PATENT OFFICE.

ELMER GEORGE GARTIN, OF CLAREMONT, NEW HAMPSHIRE.

MOTOR.

Application filed April 23, 1919. Serial No. 292,092.

This invention relates to motors and more especially to the percussive type of motors commonly used in drilling rock and other materials.

- 5 One object of the present invention is to provide an improved motor. Still another object of the present invention is to provide an improved means for supplying cleansing fluids to the tool actuated by the motor.
10 Still a further object of the present invention is to provide an improved means for controlling the cleansing fluid whereby the flow of cleansing fluid may be instantaneously regulated to remove obstructions from
15 the steel actuated by the motor or from the hole being drilled. These and other objects and advantages of my improved construction will, however, hereinafter more fully appear.
20 In the accompanying drawings I have shown for purposes of illustration two embodiments which my invention may assume in practice.

In these drawings,—

- 25 Fig. 1 is a longitudinal sectional view taken substantially on the line 1—1 of Figs. 2 and 3 through the rear end of a cylinder provided with my improvement.

Fig. 2 is an elevation of the rear cylinder head shown in Fig. 1 taken from the right hand side thereof.

Fig. 3 is an end elevation of the same head taken from the left hand side thereof.

- Fig. 4 is a longitudinal sectional view 35 taken substantially on the line 4—4 Fig. 2.

Fig. 5 is an end elevation similar to that shown in Fig. 3 but of a modified form of my improvement.

- Fig. 6 is a longitudinal sectional view 40 thereof taken substantially on the line 6—6 Fig. 5.

Fig. 7 is another longitudinal sectional view taken substantially on the line 7—7 Fig. 5.

- 45 In the illustrated embodiment of my invention shown in Figs. 1 to 4 inclusive, I have illustrated in my improved construction, a cylinder 1 having a piston 2 reciprocable therein, the latter preferably having a central longitudinal passageway 3 adapted to receive a cleansing fluid conducting means, as will hereinafter more fully appear, the rear end of the cylinder being closed by a cylinder head 4. This cylinder head is preferably retained in operative position on the cylinder 1 by side rods pass-

ing through openings 6 in the cylinder head and having heads 5 as is clearly shown in Figs. 2 and 3.

The cleansing fluids are, in the form 60 shown in Figs. 1 to 4, preferably conducted to the motor by an inlet pipe 7 which, as shown, is attached centrally to the rear of the cylinder head, and an inlet pipe 8 communicating with a controlling valve 9, the latter being operable through manipulation of a controlling handle 10 which rotates the valve in a sleeve or bushing 11. The pressure fluid which actuates the motor may be supplied to the motor in a variety of ways, 65 but in the form shown herein, this fluid is admitted from the interior of the valve 9 through a passageway 12 to an annular chamber 13, the latter in turn communicating with a plurality of longitudinal inlet passages 14 which communicate with ports opening in the cylinder, the latter not being shown herein as they form no part of the present invention.

I preferably provide means for permitting a part of the pressure fluid to flow to the cutting tool to clear the cuttings therefrom, and for this purpose, I provide in the controlling valve 9 a port 15 communicating with a groove 16, the latter in certain pre-determined positions of the valve communicating with the port 17 in the valve sleeve or bushing 11 to permit a flow of pressure fluid therethrough to a valve chamber 18 also mounted in the cylinder head 4. 90

Mounted in this valve chamber is a valve bushing or sleeve 19 having a threaded connection with the cylinder and having formed on its outer end a nut 20 by means of which the valve bushing may be removed or inserted. Reciprocatively mounted within this bushing is a hollow valve 21 herein shown as of the push button type having a push button or handle 22 formed on the outer end thereof. When the push button is in the position illustrated in Fig. 1, fluid pressure flow from the valve chamber 18 may be entirely stopped by this valve member, but I preferably provide a restricted passageway, such as a groove 23 between the valve member and the bushing within which it reciprocates for permitting a limited flow of pressure fluid past the valve. This restricted passageway communicates through suitable ports 24 with an annular recess 25 formed between the valve bushing and the cylinder head. The hollow interior 26 of

5 this valve communicates through suitable ports as shown with an annular recess 27 formed between the valve member and the valve bushing in such a manner that as the 10 push button valve is forced inwardly, the fluid from the valve chamber 18 will flow through the hollow interior 26 of the valve to the annular recess 27 and therefrom to the annular recess 25 around the valve bushing, these ports and recesses being of such 15 size that when they are in communication as just stated with the recess 25, a relatively large quantity of pressure fluid will be permitted to flow therethrough. If desired, a 20 spring may be provided for retaining the valve normally in a closed position as shown at Fig. 1, but inasmuch as the pressure of the fluid acting on the inner end of the valve is sufficient for this purpose, I preferably do 25 not use this resilient valve seating means. The recess 25 is always in communication through a passage 28 with an annular recess 29 formed between a gland plug 30 and the cylinder head into which this gland plug 35 is fastened as by a threaded connection therewith.

30 The cleansing fluids are preferably conducted by a plurality of tubes 31, 32 mounted coaxially with the cylinder and passing through the aperture in the piston to the drill steel in a manner similar to that disclosed in the U. S. patent to G. H. Gilman, No. 1,382,779, patented June 28, 1921. In the present invention, I provide an improved 35 means for holding these tubes in a proper position in the cylinder head and as shown, this means consists of a sleeve 33 which is normally pressed toward the rear end of the cylinder by a spring 34, the spring also 40 serving to maintain a packing carried within the sleeve 33 compressed so as to provide a tight joint between the different parts. Taking up the parts in the order in which they are assembled in the sleeve 33, a compressible 45 washer 35, made of leather, rubber or other suitable material, is inserted in the sleeve 33 and against this washer is placed an annular tube supporting sleeve 36 having a conical face to receive the upset end of the 50 outer tube 31 which is then inserted in the sleeve, the tube and sleeve preferably having radial ports or passages 37 communicating with an annular recess 38 around sleeve 36, this recess in turn communicating through 55 radial ports 39 with the annular recess 29, thereby establishing communication between the valve chamber 18 and the interior of the outer tube 31. Abutting against the flanged end of the tube 31 is a packing ring herein 60 shown as a steel sleeve or bushing 40 having a face fit with an end of this tube and having adjacent its opposite end, a beveled surface to receive the rear end of the inner tube 32, the latter together with the bushing 40 having 65 a face fit with the base of a socket

70 formed in the gland 30 in which socket the sleeve 33 and the parts carried thereby are held by the spring 34 when the parts are assembled as shown. The liquid supplied to this inner tube flows from the water tube 7 75 through a screen 41 and a port 42 formed in the base of the socket in the gland, the pipe 7 being detachably secured to the outer end of this gland by any suitable coupling means such as shown at 43. It will thus be 80 seen that when the controlling valve 7' on the water tube 7 is open, water will flow through the inner tube 32 to the steel and that when the controlling valve 9 is turned to admit pressure fluid to the valve chamber 18, a limited quantity of pressure fluid 85 will flow through the outer tube 31 and will mix with the water at a point at some distance from the rear head of the cylinder thereby preventing a flow of water from the 90 water inlet to the air inlet should the water pressure be greater than the air pressure. If, during the operation of the tool, the cuttings are not properly cleaned from the hole, an additional supply of pressure fluid may be 95 used for this purpose by merely depressing the push button valve 21, the ports and passages communicating with this valve being large enough to permit sufficient flow of pressure fluid to remove these cuttings at once and thereby permit an efficient operation 100 of the tool.

In the form of my improvement illustrated in Figs. 5, 6, and 7, I preferably provide a single primary controlling means for the 100 plurality of cleansing fluids delivered to the bit. This controlling means consists of a conical valve 44 to which the compressed air is conducted by a pipe 45 and the water by a pipe 46, the flow of air through the valve 105 being controlled by a port 47 passing radially through the wall of the valve and the flow of water being preferably controlled by a groove 48 formed in the outer wall of the valve and spaced longitudinally from the air 110 port 47. The air and water are conducted through separate ports 49 and 50 to a fluid conducting means extending from the rear head to the bit.

115 In this form of my improvement, I preferably use but a single conducting means, such as a tube 51 extending through the axial aperture in the piston, this tube being attached to a bushing 52 clamped between the bottom face 53 of a socket formed in the 120 cylinder head and a gland plug 54, the latter having a threaded connection with the cylinder head and carrying suitable packing means 55 to prevent leakage past the gland plug. I also preferably provide a supplemental cleansing fluid controlling means herein shown as a push button valve 56 having a valve head 57 reciprocably mounted in a socket or chamber in the gland plug 54, the valve preferably having an axial aper- 125 130

ture 59 and a port 60 adapted to receive compressed air and deliver the same to the tube 51 when the valve is in a predetermined position in the gland plug. This push button valve is preferably held in the retracted position by a spring 61, but is movable under pressure applied to the valve button 62 to control the mixture of the cleansing fluids which may be admitted to the tube 51. The flow of air from the air passage 49 to the port 60 is preferably through a plurality of annular recesses 63, 64 formed in the plug and connected by a series of radial ports 65 extending between these recesses, the latter recesses surrounding the stem of the valve and communicating with the interior thereof through the port 60 only when the valve is forced forward. The water passage 50 normally communicates with the water tube 51 through an annular recess 66 formed on the outside of the gland plug and a plurality of radial ports 67 which connect this recess with the socket 58 formed in the interior of the gland plug 54.

In the operation of this form of my improvement, when the valve 44 is turned, water and air are admitted simultaneously to the passageways 49 and 50, but the air flow is cut off by the stem of the valve, the water being permitted a free flow through the above named passages to the tube 51 and therethrough to the steel to clear the cuttings from the hole. If the tube or steel should become clogged or should the movement of the mud around the cutting tool become sluggish, the push button valve should be operated to admit a small quantity of pressure fluid to the tube 51 and thence to the bit to clear away the cuttings, or the valve may be depressed further to cut off the ports 67 and permit a free flow through the port 60 and thereby admit a relatively large flow of compressed air to the bit and supply sufficient pressure fluid to the cutting tool to quickly blow away any obstructions in the hole being drilled.

It will be noted that in my improved motor, I have provided a means for controlling the flow of a plurality of fluids to the cutting tool and have supplemented this controlling means with a second controlling means by means of which the operator may instantaneously and very easily free the cutting edge from the sluggish mixtures of water and cuttings which tend to decrease the cutting action and the efficiency of the tool, by admitting for a short period of time a relatively large quantity of compressed air or other cleansing fluid to the bottom of the hole being drilled. It will further be seen that this supplemental means is also a means for controlling the mixture of air and water. The valve shown for these purposes is a reciprocating valve which is normally held in a retracted position by fluid pressure or

spring pressure and the valve is easily operated by thumb or finger, and the degree of opening the valve may easily be regulated by the movement of the button head of the valve. It should also be noted that I have provided an improved means for securing a tube to a rear cylinder head so that a fluid tight joint is automatically maintained between this tube and the retaining means and so that the tube and the retaining means may easily be withdrawn from the motor or tool through the rear end of the rear cylinder head without otherwise disassembling the motor.

While I have in this application specifically described two embodiments which my invention may assume in practice, it is to be understood that these forms are used for illustrative purposes only and that the invention may be modified and embodied in various other forms without departing from its spirit or the scope of the appended claims.

What I claim as new and desire to secure by Letters Patent is:

1. In a rock drill, a stationary means for conducting a flow of cleansing fluid to a drill steel, valvular means operable to vary the flow of cleansing fluid thereto, and means providing a cleansing fluid leak passage always open even when said valve is in its normally closed position thereby to allow flow of cleansing fluid automatically to said steel whenever a source of pressure fluid has communication with said valvular means.
2. In a rock drill, stationary means for conducting a flow of cleansing fluid to a bit, means providing a cleansing fluid passage including valvular means adapted to limit fluid flow therethrough and inoperative to close said passage means thereby to allow flow of cleansing fluid automatically to said steel whenever a source of pressure fluid has communication with said valvular means, and means whereby said valvular means is operable from the rear of said drill to supplement the flow of cleansing fluid.
3. In a tool, means for conducting a flow of cleansing fluid to a bit, and means comprising a push button valve having a leak passage therein normally restraining the fluid flow therethrough to a relatively small quantity, said valve having means whereby when it is actuated flow of cleansing fluid to the bit may be varied while fluid flow through said leak passage is maintained.
4. In a tool, a cylinder, an apertured piston therein, a cleansing fluid conducting tube extending through the piston, means for controlling the flow of fluid to said tube, and supplemental means for controlling the flow of cleansing fluid comprising a member normally biased to a position such that a small supply of cleansing fluid is conduct-

ed to said tube and movable in a direction parallel to said tube to increase the supply of cleansing fluid thereto.

5. In a drilling apparatus, a hollow drill steel, a motor comprising a cylinder and a piston adapted to cooperate with said hollow drill steel, a cleansing fluid conducting tube extending longitudinally of the cylinder from the rear end thereof and communicating with said hollow steel, passage form-

ing means communicating with said tube, passage forming means communicating with the source of fluid supply, a ported valve adapted to connect said passage forming means via the ports thereof, and a constantly open passage passing around said valve connecting said passage forming means. 15

In testimony whereof I affix my signature.

ELMER GEORGE GARTIN.
